UNITED STATES PATENT OFFICE.

JAMES W. EASTON, OF NEW YORK, N. Y.

DYNAMO-ELECTRIC GENERATOR.

SPECIFICATION forming part of Letters Patent No. 357,705, dated February 15, 1887.

Application filed April 13, 1896. Serial No. 198,682. (No model.)

To all whom it may concern:

Be it known that I, JAMES W. EASTON, a subject of the Queen of Great Britain, residing in New York, in the county of New York, and in the State of New York, have invented certain new and useful Improvements in Dynamo-Electric Generators, of which the following is a specification.

The invention relates to the construction of 10 dynamo-electric machines and an organization of circuits adapted to operate translating devices requiring currents of greatly differing potential, such, for instance, as electric-arc lights and incandescent electric lights.

15 The object of the invention is to provide a machine adapted to automatically produce currents of the character required upon two different systems of circuits and to cause the currents supplied to one system of translating 20 devices to be entirely self-regulating, and also to so operate as to maintain a constant field of force for the production of both classes of currents, and at the same time render it possible to produce the currents required in each system 25 independently of the other, so that any accident which might render either system inoperative shall not prevent the operation of the other system.

30 The invention is especially applicable to arc and incandescent electric-lighting systems, and will for convenience be described in connection therewith, although it has other uses.

In general terms the invention consists in organizing the apparatus substantially as follows: An ordinary dynamo-electric generator 35 is provided with a system of circuits for operating the arc lights in the usual manner. Upon the armature-shaft of this generator there is carried a subsidiary armature, for which a field-magnet is provided by extending polar 40 projections from the field-poles of the main armature. The armature-coils of the subsidiary armature are connected in series with field-coils applied to these polar extensions, and 45 the incandescent electric lights are included in multiple arc between the conductors leading from the opposite poles of the subsidiary armature. The two supply-conductors for the incandescent lights are also further connected 50 by additional conductors with the respective terminals of the main field-magnet coils. These

conductors serve, in connection with the coils of the subsidiary armature, as a shunt-path around the coils of the main field, should the current generated by the main armature be 55 come too great.

The parts are so organized that the main armature will supply the currents necessary to operate the system of arc lights, while the subsidiary armature supplies the incandescent 60 lights. It is well known that in arc-light systems as usually organized a constant current is required, while in incandescent systems a constant difference of potential is necessary. The main armature is therefore provided with 65 any ordinary means for insuring a current as constant as may be required to maintain the arc lights steady and working properly, and this current should be the proper current to maintain the main field of force. The main 70 field-magnet is of practically constant resistance, and is connected, as already stated, by conductors of very small resistance to the conductors of the constant potential circuit or system. From these conditions it follows that 75 the current flowing through the coils of the main-field magnet, and consequently its magnetic force, is always practically constant, regardless of the strength or absence of the main current, unless the circuit of constant potential should become interrupted, in which case the field-magnet becomes an ordinary series field-magnet, and is wholly dependent upon the main current. Owing to the fact that the main field-magnet has a constant magnetizing 80 force as long as the source of constant potential is operative, and owing to the regulating power of the coils on the derived or subsidiary polar extensions, the subsidiary armature will preserve a constant difference of potential under 85 all ordinary circumstances without any attention. Should the normal relations be disturbed—as, for instance, should the current from the main armature increase beyond the proper amount—the excess of current will traverse the coils of the subsidiary armature and thus be shunted from the main field-magnet. Should the circuit of the subsidiary armature 90 be interrupted, the main armature will still continue to produce the current required upon 95 the arc system of circuits, because the current from the main armature should be the proper 100

current to operate the arc system; and likewise should the current operating the arc lights be interrupted the subsidiary armature would continue to supply the current necessary for the incandescent lights.

The accompanying drawing is an elevation of a machine showing in diagram an organization of circuits illustrating the invention.

Referring to the figures, A represents the armature of a dynamo-electric generator. The armature is mounted upon a shaft, B, and revolves between the pole-pieces C' and C². These pole-pieces receive their magnetization from cores F' F' and F² F², which are respectively surrounded by magnetizing-coils G' G' and G² G². The armature is provided with a collector, H, provided with two contact-brushes, i' i², and these brushes are respectively connected by conductors 1 and 2, through the magnetizing-coils, and with a main circuit, L, including the series of arc or other translating devices K K. The parts are so organized that while the coils will produce sufficient magnetism in the pole-pieces for producing the required current, yet the pole-pieces are preferably not magnetized to saturation.

Upon the same armature-shaft B with the armature A there is carried a subsidiary armature, a. This is provided with pole-pieces c' c², which are derived from the pole-pieces C' and C², being connected therewith by arms c³ and c⁴ of magnetic material. The arms c³ and c⁴ are wound with magnetizing-coils g' and g², and are connected in circuit with the coils of the armature a in such manner that currents therefrom will produce in the pole-pieces c' and c² magnetism of the same character as that which they receive by induction from the pole-pieces C' C². The armature a is provided with a collector, h, provided with collector-brushes i³ and i⁴. The brush i³ is connected by a conductor, 3, through the coils g' and g², and with a conductor, l', leading to the system of incandescent electric lights k k. These lights are connected in multiple arc between the conductor l' and a return-conductor, l², leading to the brush i⁴.

During the normal operation of the machine the currents necessary to operate the arc lights K K are derived from the armature A, and the currents of constant potential required for operating the incandescent lights k are derived from the armature a. The latter armature and the subsidiary field-magnet coils g' and g² are constructed to maintain a constant difference of potential between the conductor l' and l²; and this system serves also to maintain the field of force of the main armature constant. For this latter purpose a conductor, 5, leads from the conductor l' to one terminal of the main field-magnet coils at a point, 6, and a conductor, 7, leads from a conductor, l², to a point, 8, at the other terminal of the main field-magnet coils. These conductors form for the currents produced by the armature A a path through the armature a, together with its field-magnets, or through the translating devices k k in case the current increases beyond that necessary to maintain the main field. Should, therefore, the current produced by the armature A exceed that required through the main field-magnet coils, and should the resistance offered by these coils of the main field-magnet exceed that of the shunt through the constant potential circuit, then more or less current will be diverted around the main field-magnet coils. In this manner the fields of force for both armatures will be maintained constant and the required results attained.

I claim—

1. The combination, substantially as hereinbefore set forth, with a dynamo-electric generator, of a subsidiary armature secured to the shaft thereof, additional pole-pieces derived from the main field-magnet of the generator and applied to said subsidiary armature, independent field-magnet coils connected with the subsidiary armature-coils and applied to said derived poles, and conductors connecting the circuit of the main with the circuit of the subsidiary armature.

2. The combination, with a dynamo-electric generator, of a subsidiary armature carried upon the shaft thereof, a field-magnet for the same derived from the field-magnet of the main armature, field-magnet coils applied to the subsidiary field-magnet, and conductors leading from the respective terminals of the subsidiary armature-coils to the respective terminals of the main field-magnet coils.

3. The combination, substantially as hereinbefore set forth, with a revolving shaft, of two armatures secured thereto, two field-magnets for the same, two sets of magnetizing-coils respectively applied to said field-magnets, two systems of translating devices respectively included in the circuits of said armatures, and conductors uniting said circuits with each other.

4. In a dynamo-electric machine, the combination, with a main field-magnet, of a subsidiary field-magnet derived therefrom, and magnetizing-conductors serving to regulate the magnetization of said subsidiary field-magnet.

5. In a dynamo-electric machine, the combination, with a main magnetizing field-magnet, of a subsidiary field-magnet derived therefrom, magnetizing-conductors serving to regulate the magnetization of said subsidiary field-magnet, and a secondary armature in said subsidiary field-magnet.

In testimony whereof I have hereunto subscribed my name this 25th day of March, A. D. 1886.

JAMES W. EASTON.
